UNITED STATES PATENT OFFICE

2,584,059

CHECKING CABINET DOOR

Francis D. Stackhouse, Jr., Upper Darby, Pa., assignor to American Locker Company, Inc., Boston, Mass., a corporation of Delaware

Application May 14, 1946, Serial No. 669,621

3 Claims. (Cl. 189—46)

1

This invention relates to checking cabinets and the like and more especially to improvements in the closure door therefor. The most common use of cabinets of this nature is the automatic checking of parcels through the employment of a coin-controlled lock associated with the cabinet. The outer face of the doors of these cabinets becomes scratched and marred and frequently need to be refinished. One object of my invention consists in the provision of a sheet material panel removably associated with the door in position covering its front face, whereby permitting the removal and refinishing of the front face of the door at the factory and under conditions more economical and efficient than can be employed with the doors in place on the cabinets.

A further feature of the invention relates to an improved door having an attaching plate hingedly connected therewith and providing for the convenient and economical mounting of the door on and its removal from the cabinet, together with novel associated means providing door stop links for limiting opening movement of the door to a position giving full and free access to the cabinet.

Spring are provided for normally moving the cabinet doors to the closed position and these springs are preferably associated with the hinge joint of the door. A further feature of my invention resides in the provision of a novel hinge joint embodying two members hingedly connected on a pintle extending through a coil spring that serves the door closing function, the novel construction having provision for releasing the spring by moving the pintle longitudinally whereupon the spring can be removed or changed as required and then tensioned and its released end thereafter anchored to one of said members in proper tensioned relation. The production of a novel combination of this nature and for the purpose described comprises a further object of the invention.

These and other features of the invention will be best understood and appreciated from the following description of a preferred embodiment thereof selected for purposes of illustration and shown in the accompanying drawings in which,

Fig. 1 is a fragmentary front elevation of a bank of checking cabinets embodying my invention.

Fig. 2 is a fragmentary plan section taken on line 2—2 of Fig. 4.

Fig. 3 is a fragmentary plan section taken on line 3—3 of Fig. 4.

2

Fig. 4 is a fragmentary section taken on line 4—4 of Figs. 2 and 3.

Fig. 5 is a fragmentary vertical section taken on line 5—5 of Fig. 1.

Fig. 6 is an elevation of the hinge portion of the door in open position.

Fig. 7 is a like view illustrating a novel feature of the invention.

Fig. 8 is a plan section taken on line 8—8 of Fig. 7, and

Fig. 9 is a plan section taken on line 9—9 of Fig. 6.

In the drawings 10 indicates a bank of coin controlled checking cabinets. Each cabinet 15 embodies walls enclosing and providing a storage chamber 12 and associated with each chamber is a door 14 for closing its opening at the front. The door is adapted to be mounted on one vertical front wall 15 of the cabinet and a coin controlled lock 16 is provided on the opposite vertical front wall 17 for cooperating with the door, as described in Patent 2,222,434.

The door 14 embodies a body portion 18 constructed of sheet steel and spot welded thereto along one vertical margin is a hinge member 20. A second hinge member 22 is provided for cooperating with the member 20 and the two members are formed with cooperating hinge sections 24 in abutting end to end relation. A pintle 26 extends through aligned openings in the top sections and holds the members in hinged relation, and a second pintle 28 extends through lower sections and through a coil spring 30 in like manner. The spring is under tension with its ends 31 and 32 respectively in contact with the two members 20 and 22 for the purpose of holding the door in closed position.

The door unit, including the attached hinge members 20 and 22, is applied to the cabinet 15 merely by bolting the hinge plate 22 to the vertical front wall 15 by bolts 34. As illustrated in Fig. 2 it will be noted that the plate 22 is so applied that the pivot axis of the hinge is located along the margin of the plate more remote from the opening in the chamber, the plate having a flange 36 at its other margin for engaging the cabinet wall. Such mounting of the door provides for its opening movement to a position giving full and free access to the cabinet for inserting and removing baggage and parcels, as illustrated in broken lines in Fig. 2. Heretofore the doors have been hung at the inner margin, as illustrated in Fig. 1 of Patent 2,222,434, whereby partly obstructing the cabinet when the door is open. The major part of the door 18 embodies an inwardly directed portion adapted to enter

the chamber 12 in cooperating relation with its walls at 38 and close the front opening when the door is closed, the door being of a horizontal width reaching to and covering the vertical wall 17 but not the lock unit 16 (Fig. 4). A sheet metal reinforcing unit 40 is mounted within the door 18 and attached thereto by spot welding.

A further novel feature of the invention comprises stop links 42 for limiting opening movement of the door to the position illustrated in broken lines in Fig. 2. Two anchoring plates 44 are secured to the cabinet by the bolts 34 in position beneath the plate 22 and at the opposite side of the wall 15. One margin of each plate 44 is formed into an eye 46 which projects into a notch formed in the flange 36. Each stop link 42 has one downwardly bent end pivotally seated in this eye and its other end extends through a slot 48 in the door 18 and is provided with a head 50 in its front end serving as a stop for limiting opening movement of the door but permitting its free closing movement.

An important feature of the invention relates to a novel mounting of the spring 30 on the pintle 28 in such manner that the springs can be conveniently assembled and changed for repair purposes in the hinge and placed under the desired door closing tension. The pintle 26 permanently remains in the assembled position illustrated whereas the pintle 28 is adapted to be moved longitudinally to provide for the spring assembling and changing functions. In Fig. 6 the pintle 28 is shown in its lowermost position wherein it passes through the spring 30 and into the adjacent hinge section therebeneath. When the spring is to be assembled or changed the pintle is raised to the position of Fig. 7 whereby releasing the spring which can thereupon be removed and changed. The spring is assembled by placing its top end over the pintle (Fig. 7) with its end 31 beneath the holding lip 51. The opposite end of the spring is then turned to give the desired tension and its end 32 is finally inserted beneath the lip 52 and the pintle moved downwardly to its lowermost position. The pintle 45 can be moved longitudinally by inserting a tool in a hole 54 in its top end and one of the hinge sections is cut away at 56 to provide clearance for this movement and operation of the tool.

Another important feature of the invention relates to a removable front panel 60 for the door 14. This panel is preferably constructed from sheet metal having a front face which can be factory finished or refinished by enameling and baking in an oven. The panel is of a size substantially coextensive with the front area of the cabinet, including the opening 12 and the walls 15 and 17, and its top and bottom margins are bent over U-shaped at 62 and 64 to provide inwardly facing parallel channels or guideways for engaging top and bottom flanges 66 on the door piece 18, the panel being slidable onto the door in the direction of its hinged margin. Marginal flanges 68 (Fig. 3) are also provided on the outer end margin 70 (Fig. 1) of the panel for enclosing and covering the door when the panel is placed thereon. The panel is also cut out at 72 for exposing the lock unit 16. A handle 74 is secured to the front face of the panel by screws 75 and 76, the latter, together with bolts 78, 70 serving the function of securing the panel in place on the door. It will be noted that the nuts 79 and screw 76 can be removed only from the

inside of the door. Studs 80 provide intermediate supports for the panel on the door.

It will now be apparent that I have produced an improved door construction for checking cabinets and the like which can be most conveniently mounted on and removed from the cabinet and which swings to an open position giving full and free access to the interior of the cabinet. Novel and compact stops are mounted interiorly of the door for limiting its outward movement and novel means are provided for assembling and changing the door hinge springs for repair purposes. The door is furthermore provided with the removable front panel 60 covering substantially the entire door and cabinet and serving as convenient and economical means for keeping the cabinets in good condition and repair and of attractive appearance.

Having thus disclosed my invention what I claim as new and desire to secure by Letters Patent is,

1. A cabinet door comprising a rectangular sheet metal body having two side margins and parallel top and bottom margins, the top and bottom margins being bent laterally to provide horizontal flanges extending therealong, a sheet material panel of an area substantially commensurate with said body and having U-shaped parallel flanges along two opposite margins thereof providing parallel channels facing toward each other and receiving said horizontal flanges in sliding engagement therein, said cooperating flanges serving to guide the panel in longitudinal sliding engagement with and to a position covering the front face of said body, and removable means carried by the body and panel for securing the panel against sliding movement relative to the body.

2. The cabinet door defined in claim 1 in which said removable means comprises screw threaded means removable only from the inner face of the door.

3. The cabinet door defined in claim 1 in which the first-named flanges extend outwardly of the door and the cooperating panel flanges extend inwardly of the door, and a plurality of abutments carried in spaced relation on said body between the flanges and extending outwardly thereof into supporting engagement with the panel.

FRANCIS D. STACKHOUSE, JR.
